(57) **CLAIM**

The ornamental design for a cutting tool, as shown and described.

DESCRIPTION

FIG. 1 is a perspective view of a first embodiment of a cutting tool in accordance with the new design.

FIG. 2 is a right side view of the cutting tool shown in FIG. 1.

FIG. 3 is a left side view of the cutting tool shown in FIG. 1.

FIG. 4 is a rear view of the cutting tool shown in FIG. 1.

FIG. 5 is a front view of the cutting tool shown in FIG. 1.

FIG. 6 is a top view of the cutting tool shown in FIG. 1.

FIG. 7 is a bottom view of the cutting tool shown in FIG. 1.

FIG. 8 is a perspective view of a second embodiment of a cutting tool in accordance with the new design.

FIG. 9 is a right side view of the cutting tool shown in FIG. 8.

FIG. 10 is a left side view of the cutting tool shown in FIG. 8.

FIG. 11 is a rear view of the cutting tool shown in FIG. 8.

FIG. 12 is a front view of the cutting tool shown in FIG. 8.

FIG. 13 is a top view of the cutting tool shown in FIG. 8; and,

FIG. 14 is a bottom view of the cutting tool shown in FIG. 8.

The broken lines shown in the drawings illustrate a boundary and form no part of the claimed design.

1 Claim, 14 Drawing Sheets
